UNITED STATES PATENT OFFICE

IRVING S. ROSENBLATT, OF SAN FRANCISCO, CALIFORNIA.

ANTISEPTIC TELEPHONE-MOUTHPIECE

1,115,868.

Specification of Letters Patent.

Patented Nov. 3, 1914.

Application filed February 11, 1913. Serial No. 747,724.

To all whom it may concern:

Be it known that I, IRVING S. ROSENBLATT, a citizen of the United States, residing at San Francisco, in the county of San Francisco and State of California, have invented new and useful Improvements in Antiseptic Telephone-Mouthpieces, of which the following is a specification.

The object of the present invention is to provide a simple, cheap, convenient, and effective device to be attached to a telephone mouthpiece, to prevent the dissemination thereby of diseases resulting from germs carried into the mouthpiece with the breathing of the user thereof.

In the accompanying drawing, Figure 1 is a vertical section of a telephone mouthpiece having the device attached thereto; Fig. 2 is a similar view of the casing of the device detached; Fig. 3 is a front view of the front perforated wall of the device detached; Fig. 4 is a sectional view of the annular piece of antiseptic material used in said device.

Referring to the drawing, 1 indicates a telephone mouthpiece of the usual form and of glass, hard rubber, or any other suitable material. Fitting snugly over the outer rim of said mouthpiece and extending within

the mouthpiece about one-half its depth is a shell 2, made of aluminum or any other suitable metal. Within said shell is a tubular piece 3 of solid antiseptic material having

an outer conoidal surface formed to fit snugly within the inner surface of the shell 2, an inner surface also tapering inwardly but not to so great a degree as the outer surface, and front and rear end surfaces substantially transverse to the axis of said conoidal

surface. When said piece 3 has been pushed into place in said shell, it can, on account of the tapering forms of the piece and of the shell, only be displaced therefrom by a movement outward or to the front of the mouth-

piece. To prevent this outward movement I employ a thin annular disk 4, slightly larger than the front wall of the tubular piece, and which is placed against said front wall, and to retain it in position, its outer edge is sprung under small projections 5 formed by punching inwardly the metal of the shell.

The central hole of said disk is of the same

size as the outer end of the conoidal hole in the tubular piece 3, and thus the tubular piece of antiseptic material is very securely held in place. Said disk is formed with a large number of perforations 6 to permit the vapor of the antiseptic material to escape therethrough, and destroy all germs that might lodge on the front portion of the mouthpiece.

As the antiseptic material vaporizes, the diameter of the conoidal hole therethrough gradually increases, since vaporization takes place only from the inner surface, the outer surface, in close contact with the shell, being protected thereby from vaporization, and when said tube of antiseptic material has been wholly vaporized the annular disk can be easily sprung out of place and a new tube inserted.

When the antiseptic device is placed over the end of the mouthpiece, it is easily secured thereon by pressing its outer free edge inward around the rim of the mouthpiece.

It will be seen that my improved device is very cheap, consisting only of two metallic parts and those easily manufactured; it is easy to attach and detach from the mouthpiece; and it is very effective in use, a large extent of antiseptic surface being exposed.

I claim:

1. In an antiseptic telephone mouthpiece, the combination of an outer shell of sheet metal, a tubular piece of solid antiseptic material contained within said shell, the inner end of the shell being formed to limit the inward movement of said piece, and an annular disk of sheet metal abutting against the outer end of the tubular piece, the outer portion of the shell having an inward projection said disk being sufficiently thin to be capable of being sprung inwardly past said projection.

2. In an antiseptic telephone mouthpiece, the combination of an outer shell of sheet metal, a tubular piece of solid antiseptic material contained within said shell, the inner end of the shell being formed to limit the inward movement of said piece, and an annular disk of sheet metal removably secured to the outer portion of the shell.

3. In an antiseptic telephone mouthpiece, the combination of an outer shell of sheet

metal, a tubular piece of solid antiseptic material contained within said shell and the inner end of the shell being formed to limit the inward movement of said piece and detachable apertured means engaging only an end of said piece for limiting the outward movement thereof.

In testimony whereof I have hereunto set my hand in the presence of two subscribing witnesses.

IRVING S. ROSENBLATT.

Witnesses:
